UNITED STATES PATENT OFFICE.

ALEXANDER BLACK, OF GOUROCK, SCOTLAND.

WINDOW OR SASH OPERATING DEVICE.

No. 839,056.

Specification of Letters Patent.

Patented Dec. 18, 1906.

Application filed December 1, 1905. Serial No. 289,776.

To all whom it may concern:

Be it known that I, ALEXANDER BLACK, joiner and builder, a subject of the King of Great Britain, residing at 61 Kempoch street, 5 Gourock, Renfrewshire, Scotland, have invented certain new and useful Improvements in Window or Sash Operating Devices, of which the following is a specification.

This invention relates to windows having sliding sashes; and it has for its object to provide improved mechanical means whereby the sashes can be readily raised and lowered. The sashes are hung without weights and are or may be adapted to turn inward on hinges.

15 In order that my said invention may be clearly understood, I have hereunto appended six sheets of explanatory drawings, whereon—

Figure 1 is a front view of a window with part of the side frame broken away. Fig. 2 20 is a plan. Fig. 3 is a side view showing the raising and lowering gear. Fig. 4 is an enlarged front view, Fig. 5 a corresponding side view, and Fig. 6 a plan, of part of the gear. Fig. 7 is a front view, and Fig. 8 a plan, 25 of a special form of hinge. Fig. 9 is a front view of a window with parts of the frame broken away, so as to show a modified arrangement of sash raising and lowering gear. Fig. 10 is a plan. Fig. 11 is a side view showing the sash raising and lowering gear. Fig. 12 30 is an enlarged front view, and Fig. 13 a corresponding side view, of part of the gear. Fig. 14 is a front view of a window with part of the side frame broken away, so as to show 35 another modified arrangement of sash raising and lowering gear. Fig. 15 is a side view of the same. Fig. 16 is an enlarged front view, Fig. 17 a corresponding side view, and Fig. 18 a plan, of part of the modified gear.

40 In carrying out my invention I provide at the top of the window, and preferably within the window frame or case *a*, a horizontal shaft *b*, having at or near each end thereof a chain wheel or pulley. The pulleys are marked *c d*. Round the chain wheels or pulleys endless chains *e f* work. The lower ends of the endless chains pass round chain wheels or pulleys *g h*, which run on studs, spindles, or equivalent secured one at each side of the 45 window frame or case. There are thus two endless chains, one arranged at each side of the window. The window-sash *i* is provided with means, such as catches or staples or equivalent, whereby it can be secured to the 50 chains in such manner that as the chains are operated the sash is moved up and down. In

the case of hinged windows, as shown on the drawings, the hinge *k* of the sash is made with an extension *k'*, which works through a slot *x* in the pulley-stile and is secured to the chain 60 *e* by means of bolts *l*, Figs. 7 and 8. The angle-plate *k'* of the hinge is at the back of the slot and serves to retain the hinge horizontally in place and to guide it as it works up and down with the sash. The sash is secured to the chain *f* by means of a sliding bolt *m*, which is adapted to slip into a link in the chain.

When both sashes are adapted to be raised and lowered, then there may be two sets of 70 chain-gear at each side of the window-frame, one set for each sash. Thus the gear *e b f* is for the lower sash *i*. For the upper sash *j* there is an endless chain *e'*, which operates a wheel *c'* and rod *b'*, and there is a second 75 chain at the back of the chain *f*, which is operated by the wheel *d'* on the rod *b'*. The sash *j* can be engaged with this chain by means of a sliding bolt *n*, which when shot enters a link in the chain. The hinge *o* of 80 this sash has its extension *o'* passed through the slot *x'* and secured to the chain *e'* by means of small bolts in the same manner as the hinge *k*. Both hinges *k o* are similar in construction.

85 The chains are operated by means of wheel-gear arranged in the window frame or case and which is operated by means of a worm on a worm-shaft.

The wheel and worm gears are shown 90 clearly at Figs. 4, 5, and 6. It will be seen that the chain-wheel *g* is on a spindle *p*, carried in a housing *q*, fitted in the window frame or case. On the spindle is a pinion *r*, which gears with a wheel *s*, which latter is turned by a worm *t*. The end of the worm-spindle *t* is squared, so that it can be readily turned by a crank handle or wheel *u*, Fig. 3. The gear for operating the chain *e'* is similar. There is a chain-wheel *g'* on a spindle *p'*, carried also in the housing *q*, and on the spindle is a pinion *r'*, gearing with a wheel *s'*, which latter is turned by a worm *t'*, operated in the same manner as the worm *t*. Alternatively for economy of space the chain-wheel *g'* may be placed above or below the chain-wheel *g*, the chain *e'* working before or behind the chain *e*, and the worms and worm-wheels would be arranged accordingly.

105 It may be stated that the lower sash *i* is provided with a hinge *v*, having an extension *v'*, which is of T shape and works in the slot

x in the pulley-stile. The upper sash is provided with a similar hinge *w*, having its extension working in the slot *x'*.

With this arrangement when it is desired to raise or lower the sash *i* the wheel *s* is rotated by means of the worm *t*, whereupon the chains *e f* are caused to move the sash up or down, as the case may be. Likewise, when it is desired to raise or lower the sash *j* the wheel *s'* is rotated by means of the worm *t'*, so as to actuate the chains connected with the upper sash. When the sashes are raised or lowered the extent desired, the wheel *u* is removed, and the worm-gear securely holds the sashes in place without extraneous means. When it is desired to turn the sashes inward on their hinges, the bolts *m n* are withdrawn from their chains and the batten-rod, which is hinged, turned back out of the way.

I prefer to use only the chains at the one side of the frame (the left-hand side, Fig. 1) and dispense with those at the other side and also with the bolts *m n*. In this case as the sashes are only hung at one side small pulleys or wheels or equivalent have to be fitted to them at the other side, so as to hold them in position and facilitate the up-and-down movements. The use of pulleys or wheels for this purpose is old and forms no part of my present invention. Pulleys are shown at *i' j'*, Fig. 14.

In the arrangement shown at Figs. 9, 10, 11, 12, and 13 there is provided at the top of the window, and preferably within the window frame or case *a*, a horizontally-arranged endless chain or its equivalent *b²*, which is adapted to work on the pinions *c² d²*, secured on the upper ends of the two long screw-spindles *e² f²*, one arranged at each side of the window. The screw-spindle *e²* can be rotated by means of the worm-wheel *s²* and worm *t²*, the latter being turned by means of a handle or its equivalent *u*, which may be fitted on the squared end *t⁵* of the worm-shaft *t⁴*. (See Figs. 12 and 13.) The lower window-sash *i* is provided with screwed sockets or nuts or such like *y y'*, which work on the screw-spindles *e² f²* in such manner that when the spindles *e² f²* are rotated the sash *i* is raised or lowered. In the case of hinged windows, as shown on the drawings, the hinge *k* of the sash *i* is made with an extension *k'*, which works through a slot *x* in the pulley-stile and is secured to the socket or nut *y* in any suitable manner. The sash *i* is secured to the socket or nut *y* by means of a sliding bolt *m*, which is adapted to slip into a hole made for its reception in the socket. When it is desired to operate both sashes, there may be two screwed spindles at each side of the window and corresponding chain-gear at the top, one set of gear for each sash. Thus the gear *e² b² f²* is for the lower sash *i*, while for the upper sash *j* there is a second screw-spindle *e³* at the back of the

screw-spindle *e²*, which operates pinion *c³*, endless chain *b³*, and pinion *d³*, which is secured to another screw-spindle *f³* at the back of the screw-spindle *f²*. The sash *j* can be engaged with the screw-spindle *e³* by means of the hinge *o*, whose extension *o'* passes through the slot *x'* and is secured to the socket *y²*, working on the spindle. The sash is also engaged with the screw-spindle *f³* by means of the sliding bolt *n*, which engages with a hole in the screw nut or socket *y³* on the spindle. The whole arrangement is similar to that of the sash *i*. There is a worm-wheel *s³* on the screw-spindle *e³*, which is operated by the worm *t³*, so as to revolve the screw-spindle *e³* and raise and lower the sash *j*. *v w* are hinges for the sashes, made with retaining-guides working in the slots *x* and *x'*. If so desired, both screw-spindles *e² e³* may be operated by the same worm-gear, thus raising and lowering both sashes simultaneously. Preferably I would arrange for the sashes being secured at the left-hand side only to the screw-spindles *e² e³* and at the right-hand side provided with small pulleys or wheels adapted to run in the sash-stiles, as shown in dotted lines at *i' j'*, Fig. 14. In this case a set of screw-spindles at both sides of the window would not be required, the screw-spindles *f² f³* and chain-gears *b² b³* being dispensed with. The worm-gears for operating the screw-spindles *e² e³* are clearly shown at Figs. 12 and 13. The housing *q*, within which the lower ends of the spindles *e² e³* are carried and within which the worm-wheels *s² s³* work, is provided with side pieces or projections *q' q²*, which support the worm-shafts *t⁴ t⁵*, from whose squared ends *t⁵ t⁶* the gear is operated by means of the portable hand-wheel or equivalent *u*. With this arrangement when it is desired to raise or lower the sash *i* the screw-spindle *e²* is rotated by means of the worm *t³* and worm-wheel *s²*, thus operating the endless chain *b²*, which causes the screw-spindle *f²* to rotate. The screw-spindles *e² f²* in rotating raise or lower the sockets or nuts *y y'*, with the sash *i* secured thereto, by means of the projection *k'* on the hinge *k* and the slide-bolt *m*. Likewise when it is desired to raise or lower the sash *j* the screw-spindle *e³* is rotated by means of the worm *t⁶* and worm-wheel *s³*, thus operating the endless chain *b³* and causing the screw-spindle *f³* to rotate. The screw-spindles *e³ f³* in rotating operate the sockets or nuts *y² y³*, thus causing the sash *j*, secured thereto by means of the projection *o'* on the hinge *o* and the slide-bolt *n*, to be raised or lowered, as the case may be.

Of course instead of having an endless chain or endless chains, as the case may be, at the top of the window there may be rods provided with bevel or other gear whereby they can be rotated from the screw-spindle or spindles on the one side of the window

and may operate the spindle or spindles at the other.

If so desired, instead of operating the sashes by means of screwed spindles, as hereinbefore described, they may be operated by rack-and-pinion gear. I employ worm-gear for operating the rack-and-pinion mechanism, as such gear is self-locking.

In the modification shown at Figs. 14, 15, 16, 17, and 18 the sashes *i j* are operated by rack-and-pinion and worm gear arranged only at the left-hand side, Fig. 14, of the window-frame, the right-hand side being provided with small pulleys or wheels *i' j'*, as before described. When applied to hinged windows, as shown in the drawings, the upper end of the rack *e⁴* for the lower sash is secured to the projection *k'* on the hinge *k* of the sash *i*, while the upper end of the second rack *e⁵* is secured to the projection *o'* on the hinge *o* of the upper sash *j*. The hinges, as before, are arranged to work through the slots *x x'* in the pulley-stiles. The worm and pinion gears for operating the racks *e⁴ e⁵* are shown clearly at Figs. 16, 17, and 18. Fitted within the window frame or case is a housing *q*, with projections or side pieces *q³ q⁴*, carrying the worm-shaft *t¹⁰*, having the worm *t⁹*. The shaft is squared at its end *t¹¹*, so as to be readily turned by the hand-wheel or equivalent *u*. Gearing with the worm *t⁹* is a worm-wheel *s⁴*, on whose spindle *z* is fixed a pinion *z'*, which gears with the rack *e⁴*. The gear for operating the rack *e⁵* is similar. There is a worm *t¹²* on a worm-shaft *t¹³*, with a squared end *t¹⁴*. The worm-shaft *t¹³* is supported between the projections *q⁵ q⁶*, provided in the housing *q*. Gearing with the worm *t¹²* is a worm-wheel *s⁵*, on whose spindle *z²* is fixed a pinion *z³*, which gears with the rack *e⁵*. The housing *q* is also provided with a number of small rollers *q⁷*, which bear on the backs of the racks *e⁴ e⁵* and hold them in engagement with their pinions *z' z³*. With this arrangement when it is desired to raise or lower the sash *i* the spindle *z* is rotated by means of the worm *t⁹* and worm-wheel *s⁴*, thus rotating the pinion *z'* and causing the rack *e⁴*, with the sash *i* attached thereto, to be moved up or down, as the case may be. Likewise when it is desired to raise or lower the sash *j* the spindle *z²* is rotated by means of the worm *t¹²* and worm-wheel *s⁵*, thus rotating the pinion *z³* and operating the rack *e⁵*, with the sash *j* attached thereto.

Both racks *e⁴ e⁵* may, if so desired, be operated by the same worm and pinion gear, thus operating both sashes *i j* simultaneously. In most cases it is sufficient to have merely the rack, pinion, and worm gear for operating the upper sash only.

It is very important to have the sashes hinged to either the screw or the rack, as the

case may be, and it is equally important to have the worm-gear, as the latter insures the sash being locked in any position. No amount of pushing of the sash will overcome the worm-gear, and therefore when closed the sashes are burglar-proof.

Having now fully described my invention, what I claim, and desire to secure by Letters Patent, is—

1. The combination with a sliding sash, of mechanical means for raising and lowering it, means for enabling the sash to be turned inward, said sash being hinged to the raising and lowering means and worm-gear for operating said mechanical means.

2. The combination with a sliding window-sash, of mechanical manually-operated means in front of the window for both raising and lowering the sash, hinges on the sash, means for connecting the hinges to the mechanical means and worm-gear for operating the said mechanical means.

3. The combination with a sliding window-sash, of mechanical manually-operated means for raising and lowering the sash, means for permanently connecting the one side of the sash to the said mechanical means, means for temporarily connecting the other side of the sash to said mechanical means and worm-gear for operating the mechanical means.

4. The combination with a sliding sash hinged at one side thereof, of a screw, means for connecting the hinges of the sash to the screw, and worm-gear for operating the screw.

5. The combination with a sliding sash, of hinges therefor said hinges having extensions, guides for the extensions, a screwed socket secured to the extension of one of the hinges, a screwed spindle and worm-gear for turning the spindle.

6. The combination with a sliding sash hinged to its raising and lowering means, of two screwed spindles, means for permanently securing the sash to one spindle, means for temporarily securing it to the other spindle, worm-gear for rotating one spindle and means for transmitting the motion from the one spindle to the other.

7. The combination with a sliding sash, hinged to its raising and lowering means, of two screwed spindles, a socket on each spindle, means connecting the sash permanently to the one socket, a sliding bolt for attaching the sash to the other socket, means for transmitting motion from one spindle to the other and worm-gear for operating one spindle.

In testimony whereof I affix my signature in presence of two witnesses.

ALEXR. BLACK.
